(57) **CLAIM**

I claim the ornamental design for the bucket-scraping apparatus, as shown and described.

DESCRIPTION

FIG. 1 illustrates a rearward side perspective view of my design for a bucket scrapping apparatus;

FIG. 2 illustrates a top perspective view thereof;

FIG. 3 illustrates a bottom perspective view thereof;

FIG. 4 illustrates a rearward elevation view thereof; and,

FIG. 5 illustrates a forward elevation view thereof.
